UNITED STATES PATENT OFFICE.

RIVERIUS MARSH, OF NEW BRUNSWICK, NEW JERSEY.

DESIGN FOR A LAMP-CHIMNEY.

SPECIFICATION forming part of Design No. 25,511, dated May 19, 1896.

Application filed December 19, 1895. Serial No. 572,721. Term of patent 3½ years.

To all whom it may concern:

Be it known that I, RIVERIUS MARSH, a citizen of the United States, residing at New Brunswick, Middlesex county, and State of New Jersey, have invented and produced a new and original Design for a Lamp-Chimney to be used more particularly for that class of lamps known as "Welsbach Burners," and are for either oil or gas, of which the following is a specification.

My invention relates to a novel design for the chimneys of gas and other lights; and the leading feature consists in the peculiar shape or configuration given thereto, whereby a neat and ornamental appearance is given to the same, which is attractive to the eye.

The accompanying drawing represents a side elevation of a lamp-chimney made in accordance with my design.

In the said drawing the reference-letter A ²⁰ designates the upper section of the chimney, made cylindrical in form and provided with ornamental peripheral beads *a a*.

The letter B designates the lower cylindrical section, to which are secured a number ²⁵ of vertical ornamental rods *a²*, the outer edges of which are formed with a number of alternating curved depressions and projections constituting wave-like corrugations.

The letter *a'* designates an ornamental ring ³⁰ encircling the upper ends of said rods.

What I claim is—

The design for a lamp-chimney herein shown and described.

RIVERIUS MARSH.
